UNITED STATES PATENT OFFICE

165,340

TOY FIGURE

George W. Owen, Columbia, S. C.

Application December 4, 1950, Serial No. 13,259

Term of patent 7 years

(Cl. D34—15)

To all whom it may concern:

Be it known that I, George W. Owen, a citizen of the United States, residing at Columbia, State of South Carolina, have invented a new, original, and ornamental Design for a Toy Figure, of which the following is a specification, reference being had to the accompanying drawing, forming a part hereof.

Fig. 1 is a front elevational view of a toy figure, showing my new design.

Fig. 2 is a side elevational view thereof.

Fig. 3 is a top plan view thereof.

I claim:

The ornamental design for a toy figure, substantially as shown.

GEORGE W. OWEN.
